UNITED STATES PATENT OFFICE

IRVING A. EICHENBAUM, OF NEW YORK, N. Y.

HAT MAKING MACHINE

Application filed August 11, 1930. Serial No. 474,435.

This invention relates to blocking and finishing machines in general, and particularly to the kind specially adapted for finishing and refinishing felt hats.

One of the objects of this invention is to provide a hat finishing machine by means of which an already manufactured hat may be cleaned, brushed, pressed, steamed and subjected to other cleaning and finishing 10 operations required for enhancing the good appearance of a hat.

Another object of this invention is to provide a machine which will block a hat, rotate it in either clockwise or anti-clockwise 15 directions, while at the same time reciprocating it, and which is provided with a finishing tool and means for raising and lowering the latter and guiding or maintaining it in a predetermined relation to the hat during 20 the operation of finishing it.

Another object of this invention is to provide in connection with this machine an exchangeable and adjustable profile element adapted to cause the desired movement or 25 movements of the finishing tool relative to the hat.

Another object of this invention is to provide a multiple finishing tool comprising a plurality of individual tools for brushing, 30 buffing, ironing and luring a hat.

Another object of this invention is to provide means for steaming the hat.

Another object of this invention is to provide with the machine a device for heating 25 or drying the hat during or after being subjected to the finishing operations.

Still another object of this invention is to provide means within the machine for automatically causing the operation of the various devices, first in one and then in another 40 direction, each means having provision for manually controlling them.

Other objects and advantages of the invention will be hereinafter specifically pointed out, or will become apparent, as the specification proceeds.

With the above indicated objects in view, the invention resides in certain novel constructions and combinations and arrangements of parts, clearly described in the fol-

lowing specification and fully illustrated in the accompanying drawings, which latter show embodiments of the invention as at present preferred.

In said drawings:

Fig. 1 is an elevation of a preferred form 55 of my device partially in cross-section.

Fig. 2 is a top view thereof with some of the parts removed.

Fig. 3 is a side elevation of the machine 60 showing the general arrangement and particularly the hat drying mechanism.

Fig. 4 is a detail view of the reciprocating mechanism for the hat block support taken on line 4-4 of Fig. 1.

Fig. 5 illustrates a partial detail view of 65 the profile element or pattern employed in my device.

Fig. 6 illustrates a top view of a steam control valve associated with my device.

Fig. 7 is a side elevation thereof.

Fig. 8 is an enlarged detail view of my 70 multiple finishing tool; and

Fig. 9 is a side elevation thereof.

Referring to the drawings, illustrating one 75 of the possible embodiments of my invention as at present preferred, numeral 10 denotes a frame of work-table 11 adapted to support the various parts of my mechanism, which consists of a motor 12, illustrated in Fig. 2, 80 which transmits power by means of gears 13 to driving shaft 14, which is lodged in bearings 15 and 16 in frame 10.

Slidably keyed to the shaft 14 will be seen 85 couplings 17 and 18, adapted to engage idling members 19 and 20 forming portions of miter gears 21 and 22 respectively. These miter gears engage a vertically rotatable gear 23, which is pinned to vertical shaft 24 journaled in bearing 25. To the enlarged 90 portion 26 of shaft 24 is attached horizontal gear 27 and another horizontal gear 28. Gear 28 engages horizontal gear 29 keyed to shaft 30 and journaled in bearings 31 and 32.

Disposed above bearing 32 there is keyed 95 to shaft 30 a coupling member 33 adapted to be engaged by a loose clutch member 34, controlled by handle 35. Loose clutch member 34 is hollow and at its upper portion there is attached thereto an eccentric 36.

At the upper end of shaft 30 there is provided a double universal joint 37 capable of a rotary and reciprocating motion. The upper portion 38 of the joint is guided in a slot 39 and comprises a slide 40, guided in a frame 41.

Slot 39 is provided within the work-table and also accommodates beside the joint end 38 an eccentric engaging member 42 depending downwards from slide 40, and provided with a friction reducing arrangement indicated at 43 and comprising a roller vertically mounted with engaging member 42. Through slot 39 also extends a bracket 44, the lower end of which is engaged by a coil spring 45 attached at 46 to bearing support 47.

Spring 45 is adapted to exert constantly a pull upon bracket 44, thereby causing slide 40 to bear in left hand direction, as shown in Fig. 1.

Extending from guide 40 above joint end 38 there will be seen mounted a vertical shaft 48, to which is keyed the hollow extension 49 of block support 50, adapted to receive an exchangeable hat block 51. Hollow block support extension 49 is preferably adjustable relative to shaft 48 by means of wing screws 52.

Attached to block support extension 49 there will be seen a tray 53 adapted to extend beyond block support 50 so as to prevent any refuse, dust, etc. from entering the mechanism operating the block support.

In the rear of the block support there will be seen a standard 54 extending from work-table 11 upwards and forming a support for a hat drying mechanism, which consists of a bracket 55 provided with a pivot 56, at which is fulcrummed a lever 57 normally held in upward position by means of a spring 58 engaging end 59 of lever 57 and attached at 60 to table frame 10.

Lever 57 is provided with a substantially vertical hinge connection 61 at which is attached hand lever 62, adapted to be pulled downwards manually by means of handle 63. At the first bend of lever extension 62 there will be seen provided a hinge connection 64, from which depends a suspending arm 65, connected with a hat drying die 66. The latter consists of a hollow body adapted to receive the hat mounted on block 51 and is provided with handles 67 and a gas heater connection 68.

Upright shaft 48 of the hat block support is preferably hollow and extends into the hat block support portion 50, which is also preferably hollow as is the hat block itself. The latter, while not so shown, is preferably provided with a plurality of minute perforations so as to permit steam entering shaft 48 to penetrate through the perforations into the hat material when so desired. The steam connections are not shown. However, at the left

side on the work-table, as seen in Fig. 1, there is illustrated a steam control valve 69, which is operated by means of a valve handle 70, shown in Figs. 6 and 7 in detail, by means of lever 71 forming part of the control mechanism of my machine.

Referring to the right hand portion of Figs. 1 and 2, it will be observed that horizontal gear 27 of the drive mechanism of my device engages a similar horizontal gear 72, which is keyed to shaft 73 journaled in vertical bearing 74. Shaft 73, extending upward at 75, is provided with a long key 76, adapted to engage an outwardly threaded hollow spindle 77.

A portion of the work-table 11 is provided with an enlargement in the form of a casing 78, which is provided with an internally threaded aperture 79, adapted to be engaged by spindle 77. At both sides of the spindle engaging portion of casing 78 there will be seen vertical side guides 80, in which slide guide bars 81 depending from tool support frame 82. The latter is provided with a central aperture 83, through which passes the upper extension 84 of sleeve spindle 77. This extension 84 is rotatably mounted in aperture 83 so as to permit a free movement of spindle 77.

Right below the center portion of tool support 82 and attached to spindle extension 84, there will be seen a collar 85 permanently secured and provided with a pawl 86. A similar collar 87 will be seen attached to spindle 77 and equipped with a similar pawl 88.

Hingedly associated with tool support 82 at 89 there will be seen two parallel bars 90 extending upwards and provided with hinge connections 91 at their upper ends. With these connections there are associated depending lugs 92 of tool rest 93.

As will be readily seen from Fig. 1, parallel bars 90 being hinged at both ends, are capable of a swinging motion, and in order to assure these bars to assume normally a vertical position, as shown in Fig. 1, coil springs 94 are provided at each hinge connection of the bars.

At the right hand end of tool rest 93 there will be seen provided adjustably mounted extension 95 equipped with an anti-friction roller 96, which latter is in engagement with a pattern 97, adjustably mounted in standard 98 extending from the right hand edge of work-table 11.

Pattern 97 is exchangeable and is provided with a profile edge 99, which is engaged by roller 96.

At the right hand end of tool rest 93 there will be seen a hinged bracket 100, to which is attached a multiple finishing tool 101 at 102, and which latter comprises a number of individual hat finishing tools, as will be explained presently. The center portion of the

multiple tool is provided with a rest pin 103, adapted to support the tool when swung in right hand direction and out of engagement with the block support 50.

The operation of the multiple tool, the tool rest 93, and the tool support 82, is as follows: While spindle 77 is rotated in anti-clockwise direction by shaft 75, tool support 82 is moved upwards causing the tool rest to swing in left hand direction, due to the fact that it is pushed in that direction by extension 95 engaging profile 99 of pattern 97. In that manner the individual tool, adapted to engage the hat on block 51, moves thereagainst while the latter rotates. The upward movement continues until roller 96 reaches its uppermost position, shown in broken lines in Fig. 1, and then spindle 77 is caused to revolve in the opposite direction, whereby the tool support 82 is caused to descend and tool rest 93 swings back in right hand direction to its normal position when it reaches its lowermost stand.

The upward and downward movement of spindle 77 is controlled by a lever arrangement best seen in Figs. 2 and 3. At the front edge of table frame 10 there will be seen a guide bracket 104, in which oscillates a lever 105 provided with a handle 106. Lever 105 is pivoted at 107 and is provided with an extension 108 terminating in a hinge connection 109, in which is mounted a bracket 110 engaging an operating rod 111.

Operating rod 111 is shown in cross-section in Fig. 1 and is held in place by means of set collars 112, attached to sliding rod 113, guided at its ends as shown at 114. Rod 113 is capable of reciprocation caused by lever 105.

Attached to rod 113 there will be seen bifurcated members 115 engaging loose coupling members 18, keyed to shaft 14.

At the upper end of bar 105 there will be seen attached at 116 connecting levers 117 and 118, clearly seen in Fig. 2. These levers engage at their free ends actuating levers 119 and 120 respectively, which are pivoted at 121 as clearly seen in Fig. 2. These actuating levers are adapted to be engaged by pawls 88 and 86, respectively, while threaded spindle 77 travels in downward or upward directions.

To start the machine handle 106 is swung to the right. By so doing actuating lever 120 is caused to swing with its outer end in right hand direction and with its spindle pawl-engaging end in left hand direction. Lever 119 however is moved with its inner pawl-engaging end against the spindle.

By operating handle 106 in right hand direction the right hand yoke 115 causes coupling member 17 to engage coupling member 19, thereby causing the operating mechanism of the spindle to revolve in anti-clockwise direction. At the same time spindle 30, controlling the operation of block support 50, is also caused to rotate in anti-clockwise direc-

tion. When the spindle 77 reaches a point where collar 87 arrives at the plane of lever 119, pawl 88 engages that lever and causes the same to move in right hand direction, thereby imparting a left hand movement to bar 105. This movement of the bar causes the disengagement of coupling member 17 from coupling member 19 and the engagement of friction member 18 with friction member 20. This change reverses the operation of spindle 77 and also of spindle 30 of the mechanism.

Through the movement of lever 105 actuating lever 120 is also caused to engage with its operating end spindle 77. When the reversal of movement of spindle 77 has taken place, the latter descends until collar 85 with its pin or pawl 86 reaches the plane of lever 120. The moment pawl 86 engages lever 120 it pushes the latter in left hand direction thereby causing bar 105 to assume its normal central position shown in Fig. 2, which causes disengagement of clutch member 18 from clutch member 20. At this moment all operations above the table stop and in order to bring the machine into operation again it is required that handle 106 is thrown in right hand direction.

It will be observed that pin 88 is considerably longer than pin 86. The difference in length of these pins causes a difference in operation, thus pin 88 being longer throws lever or bar 105 a full stroke to its extreme left hand position, while the operation of pawl 86 causes bar 105 to move only half way into its normal middle position explained above.

Referring to Figs. 8 and 9, the construction of my multiple tool consists of a center arbor 122, controlled by a clamping handle 123 by means of which the position of the individual tools attached to body 124 of the multiple tool may be adjusted in desired relation to hat block 51.

In each corner of body 124 there will be seen individual tool rests 125, 126, 127 and 128. Each one of these tool rests consists of a socket 129, in which is lodged a spring 130 bearing against the end face of tool pin 131, which is preferably provided with a slot 132, adapted to be engaged by set screws 133.

Tool pin 131 extends from a tool supporting frame 134, which is provided with end sockets 135, in which are mounted spring controlled tool supporting rods 136, which form extensions of tool supporting heads 137. These heads are provided with adjusting slots 138, through which pass adjusting screws 139 extending from tool ends 140 arranged between heads 137. These tool ends are pivotally mounted by means of screws 141 in tool heads 137.

The left hand tool shown in Figs. 8 and 9 comprises what is known as an ironing tool, which is electrically heated and which is preferably equipped with a handle bar 142. The

ironing tool consists of heated block 143, which is preferably held under tension by means of spring 144. The tool indicated at the upper end of Fig. 8 and extending from socket 127 is what is known as a sand-buffing tool and consists of a sand paper block adapted to roughen the surface of the hat. The right hand tool shown in Fig. 8 is what is known as a luring tool and consists of a soft felt pad provided with press cloths on top. A similar tool is shown on the lower end of Fig. 8 extending from socket 125, which is similarly built as that shown on the right hand side, but may be provided with either a rougher or smoother cloth surface than the formerly mentioned luring tool. The luring tools are all heated.

Operation.—The different movements of my machine having been explained in connection with the description of the drawings, the function of my device is as follows: A proper hat block 51 is secured to block support 50 and a hat is mounted on hat block 51. A pattern with a proper profile is attached and adjusted in standard 98 and the required individual tools are mounted in the multiple tool head 101. It is usual that first the buffering tool is employed in order to roughen up the surface of the felt of the hat form and the hat block is rotated first in one and then in the opposite direction while subjected to the buffering operation. Then the tool head is turned ninety degrees and either one of the luring tools comes into action and the operation of the machine is repeated. The first luring operation may be then followed by another luring operation, and after the hat form is considered to be otherwise finished the ironing tool is applied.

The various applications of the individual tools is more or less left to the choice of the operator as it depends entirely upon the material of the hat form which one of the operations is to be employed first, repeated, or entirely left out.

In some cases the hat form has to be cleaned and may be subjected to a wet cleaning process, which requires drying or partially drying of the hat form on the block, in which case the application of drying mechanism 66, shown in Figs. 1 and 3, is employed.

The reciprocating movement of block support 50, while rotating in either clockwise or anti-clockwise directions, is accomplished by the co-operation of eccentric 36 with eccentric engaging member 42 and spring 45. The latter tends to pull slide 40, in which is revolvingly lodged shaft 48, in a left hand direction, while eccentric 36, when in the position shown in Fig. 4, presses against member 42, thereby forcing slide 40 in a right hand direction.

This reciprocating movement of slide 42 may be terminated by sliding clutch member

34 out of engagement with clutch member 33, through an upward pull of lever 35.

The hereinbefore described construction admits of considerable modification without departing from the invention; therefore, it is the wish not to be limited to the precise arrangements shown and described, which are as aforesaid, by way of illustration merely. In other words, the scope of protection contemplated is to be taken solely from the appended claims, interpreted as broadly as is consistent with the prior art.

What is claimed is:

1. A hat blocking and finishing machine, comprising in combination a clockwise and anti-clockwise rotatable and reciprocating hat block support, a hat block mounted thereon, a tool support raising and lowering mechanism, a reciprocatingly mounted tool support carried thereby, a rotatable turret adapted to receive a plurality of tools and disposed in operative relation to said hat block, a profile following member extending from said support, an exchangeable profile element in engagement with said member, operating means for actuating said block support and said tool mechanism, and means in operative relation with the latter for controlling said operating means.

2. In a hat blocking and finishing machine, a work table, a hat block support operatively mounted thereon and comprising a base resting upon said table, double universal connecting means depending from said support, a vertically journaled operating spindle joined by said connecting means with said support, a clutch device associated with said spindle and comprising two parts, one in permanent connection with the spindle, the other being hollow and slidable upon said spindle and adapted to engage said permanently connected part, when desired, an eccentric associated with hollow clutch part and adapted to rotate with the spindle when the clutch parts are in operative engagement, an eccentric engaging member extending from said block support through said table, guide means provided for said member in said table, a spring arrangement connected with said block support and adapted to pull the latter in one direction, said eccentric and said engaging member adapted to move said block support in opposite direction while the latter is rotated by said spindle.

3. The combination with a hat blocking and finishing machine, of a hat block support operating mechanism, comprising a vertical spindle, a coupling device associated therewith and composed of one member keyed to the spindle and another, operative member in sliding engagement with said spindle and provided with actuating means for facilitating engagement with or disengagement from said first mentioned coupling member, a cam associated with said operative member, a uni-

versal coupling link extending from said spindle above said cam, a guided slide operatively associated with the upper end of said link, a cam engaging member depending from said slide adapted to transmit the motion of the cam to the latter, and thereby to the upper end of said link, a spring associated with said slide and adapted to exert a pull thereon in a direction opposite to that induced to the slide by the operation of said cam.

4. A hat blocking and finishing machine, comprising in combination with a work table, an operatively mounted hat block support, an exchangeable hat block attached thereto adapted to receive a hat to be finished, a rotary and reciprocating mechanism connected with said hat block support and having means for imparting to the latter an either clockwise or anticlockwise rotation, while the support reciprocates, a tool support operating mechanism, in operative connection with said block support mechanism, comprising raising and lowering means, a reciprocatingly mounted tool support associated with the latter and provided with a friction reducing contact member, an exchangeable, adjustably supported profile element in constant engagement with said tool support adapted to follow the contour of said profile element as it is being raised or lowered, a multiple tool carried by said support and adapted to engage a hat mounted upon said hat block while the latter rotates and reciprocates, a power transmitting mechanism in engagement with said block support mechanism and said tool mechanism, machine operation controlling means interposed between and forming parts of said tool support mechanism and said power transmitting mechanism and having means for manually starting or stopping the operation of the machine, said hat block support mechanism comprising a rotary spindle, a double universal connection between the spindle and said block support, a clutch device associated with the spindle, an eccentric connected with the idler and of said coupling device, an eccentric engaging member associated with said block support beyond said universal connection, guide means provided for said engaging member, means connected with said block support for causing the operation of the latter in one direction while permitting its movement in opposite direction when actuated by the co-operation of the eccentric with said engaging member, while the coupling device operatively connects the eccentric with said spindle.

In testimony whereof I hereby affix my
signature.

IRVING A. EICHENBAUM.
